US00D494574S1

(12) **United States Design Patent** (10) Patent No.: **US D494,574 S**
 Schmidt et al. (45) Date of Patent: **** Aug. 17, 2004**

(54) **HEADSET AMPLIFIER**

(75) Inventors: **Peter Schmidt**, Campbell, CA (US);
Jeffrey S. Jones, Los Altos, CA (US);
John Magnasco, San Jose, CA (US);
Ron Van Thiel, Menlo Park, CA (US);
Paul Espinola, San Jose, CA (US)

(73) Assignee: **Hello Direct, Inc.**, San Jose, CA (US)

(**) Term: **14 Years**

(21) Appl. No.: **29/160,893**

(22) Filed: **May 17, 2002**

(Under 37 CFR 1.47)

(51) LOC (7) Cl. **14-03**

(52) U.S. Cl. **D14/240**

(58) Field of Search **D14/248-256, D14/433; 379/93.06, 93.15, 156, 165, 900, 93.09, 338, 339, 454; D13/147**
